UNITED STATES PATENT OFFICE.

EDWARD FORBES PICKETT, OF BUFFALO, NEW YORK.

ROTARY ENGINE.

SPECIFICATION forming part of Letters Patent No. 702,675, dated June 17, 1902.

Application filed January 23, 1902. Serial No. 90,938. (No model.)

To all whom it may concern:

Be it known that I, EDWARD FORBES PICKETT, a citizen of the United States, residing at Buffalo, in the county of Erie, State of New York, have invented a new and useful Improvement in Rotary Engines, of which the following is a specification.

This invention relates to the class of rotary engines in which a piston-cylinder is pivoted concentric with the steam-cylinder.

The object of my invention is to provide a rotary engine having a limited number of moving parts and adapted to receive fluid energy during a portion of its revolution, to expand the said fluid in compound cylinders, to avoid a dead-center and permit starting the engine with the piston in any position, and rotate in either direction.

I do not limit myself to the use of any particular fluid-pressure as a moving agent; but for convenience in describing the operation of the engine I will designate steam as the motive power.

In the accompanying drawings like letters of reference show like parts, and the darker-section lining shows the moving cylinder or piston.

Figure 1 is a vertical section of a compound expansion-engine, taken through the small steam-chamber. Fig. 2 is a vertical cross-section through both chambers. Fig. 3 shows the gear arrangement for reversing the exhaust-valve. Fig. 4 is a vertical section showing the piston-lug of the first or high-pressure chamber passing under and displacing the first abutment. This figure also shows a modification of the exhaust-valve. Fig. 5 is a horizontal section on line H H, Fig. 4. Figs. 6, 7, and 8 show modifications in the arrangement of parts.

Referring to Figs. 1 and 2, the engine is provided with two parallel steam-chambers designed for high and low pressure and lying between two concentrically-arranged cylinders. The stationary cylinder A is formed with an annular partition α , which is bored to fit the outside diameter of the piston B and separates the two steam-chambers. A segmental recess whose radius extends to the outer diameter of the piston is formed on each side of the said partition. Abutments C and C', having radial wings of equal length, which

insures equal pressure against the wings, are pivoted in the said recesses, and each abutment moves independently of the other. 55 Springs n and n' , secured to the pivots, hold the abutments in a line vertical to the engine-axis and with one wing touching the outer cylinder, while the other contacts with the rotary piston. The piston-cylinder is provided with lugs p and p' , fitting the steam-chambers and consisting, preferably, of tubular steam-packing or other suitable material secured to a spring, which holds the lug against the bore of the outer cylinder. The lugs are 60 designed to displace the abutments by impact and cause them to rotate or oscillate with every turn of the piston, and they are so arranged that when one abutment is opened the other will be closed, thus preventing a dead-center. 65 This may be effected by placing one pair of either the abutments or the lugs with one out of alinement with the other of the same pair. An opening which I will term the "transfer-passage" d and d' is arranged to deliver 70 steam after the first expansion into the second or low-pressure chamber and opens from the left of the abutment C in the first steam-chamber to the right of the abutment C' in the second chamber. Thus when the expanding steam enters the second chamber it impacts against the second lug in the same direction in which the engine may be rotating. The steam-ports which communicate with the expansion-chambers terminate in the 75 journal of the piston-cylinder and are arranged in combination with the exhaust-ports as follows: An inlet-port i and an exhaust-port e open into the first chamber at the right of the abutment C, and similar ports i' and e' 80 open into the second chamber at the left of abutment C'. Thus each steam-chamber is provided with a supply and an exhaust port on the opposite side of the abutment to the entrance of the transfer-passage. A tubular 85 shaft I is journaled in the piston-cylinder and remains stationary during the rotation of the engine. The shaft is provided with an aperture adapted to register with either inlet-port, according to the direction in which the engine moves. An exhaust-valve E is fitted in the partition and provided with an aperture h , adapted to register with the exhaust-ports 90 e and e' , and thus withdraw the expanded 95 steam.

steam from either chamber. The lever L is fulcrumed on the side of the engine and may turn or reverse the exhaust-valve by means of a rack and gear, as shown in Fig. 3, 5 and it also moves the supply-shaft by means of bevel-gears either longitudinally to direct live steam into either chamber or it may be rotated to bring its aperture in register with the inlet-port, as may be necessary in starting 10 the engine. The shaft is rotatably held in a sleeve which carries the gear attached to the lever, and the other gear-wheel is fixed to the shaft, as shown. A pulley-shaft s extends outwardly from the piston and affords means 15 for the transmission of power by pulley or otherwise.

In Figs. 4 and 5 the exhaust-valve E is fitted in a bore parallel to the engine-axis and directly secured to the hand-lever, by 20 which it may be drawn in or out to open either exhaust-port. I do not limit myself to placing either the exhaust valve or ports in any special position, the object sought being to withdraw steam from each chamber at 25 points opposite to one another in relation to the abutments.

To conveniently illustrate the operation of the engine, I have indicated the movement of live steam by a double-arrow mark, the 30 transfer of steam into the second chamber by a single arrow, and the final exhaust by a dotted-arrow mark.

In starting the engine the supply-shaft will be moved inwardly to admit steam through 35 its aperture into the inlet-port i, and the rotation of the piston over the shaft will cut off the supply after one quarter-turn. The steam then enters the high-pressure chamber to the right of the abutment C, Figs. 1 and 2, 40 which, being balanced, receives the impact equally on both wings and remains stationary. The steam-pressure on the lug p rotates the piston-cylinder to the right, and when one revolution is completed the partially-expanded steam enters the low-pressure chamber at the right of abutment C'. The steam expands against p' during another rotation of the piston and then exhausts 45 from the port e' and through the aperture h of the exhaust-valve E, Figs. 2 and 5. In reversing the engine the handle of the lever is moved inwardly, and the opposite exhaust-port e is opened, and the shaft I is drawn out to direct the steam-jet into the inlet-port i'. 50 The steam then enters the second chamber for its initial impulse and expands at the left of the abutment, rotates the piston to the left, and exhausts from the first chamber.

In order that no dead-center shall occur 60 when starting the engine, the piston-lugs p and p' are out of alinement, so that one precedes the other in passing an abutment, as shown in Figs. 4 and 5. In this case assume the engine at rest, with the lug p under the 65 abutment C, and it is desired to start the engine to the right. The steam entering the inlet-port i would have no effect on the lug p.

It will, however, pass through d and d' into the second chamber, and the abutment C' being closed allows the steam to expand between it and the second lug p', thereby starting the engine. When the first lug p is moved sufficiently to allow the abutment C to assume its normal position, the steam-jet from the same port i will at once act in the first chamber and against the lug p, entering the second chamber only after the first expansion is completed. 75

In Figs. 6 and 7 the abutment is modified and arranged to rotate one quarter-turn with 80 every stroke of the piston. The exhaust and inlet ports are placed in the inner cylinder, and the exhaust-valve as well as the supply-pipe are fitted in the journal of the engine, and both are movable longitudinally to open 85 their respective ports. In this case the outer cylinder carries the piston-lug, a side view of which is shown at Fig. 8.

I claim—

1. A rotary engine comprising a stationary 90 cylinder or body, annular steam-chambers, one arranged for high pressure and the other for low pressure, an abutment in each chamber, a rotary piston having a lug fitting each chamber, said lugs being out of alinement 95 with each other, a passage connecting one steam-chamber at the left with the other chamber at the right of the said abutments, an inlet and an exhaust port opening from each chamber on the opposite side of the abutment 100 to the entrance of the said passage, a supply-pipe adapted to admit steam into either inlet-port, and an exhaust-valve arranged to withdraw steam from either exhaust-port, substantially as described. 105

2. A rotary engine comprising a stationary cylinder or body, an annular partition separating two steam-chambers, said chambers arranged for high and low pressure, a movable abutment pivoted in each chamber, a rotary 110 piston concentric with the said stationary cylinder and having a lug fitting each chamber, said lugs being out of alinement with each other, a passage connecting one steam-chamber at the left with the other chamber at the 115 right of the said abutments, an exhaust-port in each chamber on the opposite side of the abutment to the entrance of the said passage, inlet-ports arranged to admit steam into one chamber at the left and into the other chamber 120 at the right of the said piston-lugs and between the lug and the abutment, a supply-shaft journaled in the engine and arranged to admit steam into either inlet-port, an exhaust-valve adapted to withdraw steam from 125 either exhaust-port, and a lever engaging the said shaft and exhaust-valve and adapted to move them for the purpose of opening or closing the said inlet or exhaust ports, substantially as described.
